G. W. MULLER

RAILWAY TIE CONSTRUCTION

Filed July 9, 1925

Patented Mar. 30, 1926.

1,579,021

UNITED STATES PATENT OFFICE.

GEORGE W. MULLER, OF WASHINGTON, DISTRICT OF COLUMBIA.

RAILWAY-TIE CONSTRUCTION.

Application filed July 9, 1925. Serial No. 42,539.

To all whom it may concern:

Be it known that I, GEORGE W. MULLER, citizen of the United States, residing at Washington, District of Columbia, have invented certain new and useful Improvements in Railway-Tie Construction, of which the following is a specification.

This invention relates to railway construction, and has for one of its objects to improve and strengthen the rail supports, to enable them to withstand the increased weight of the modern locomotive and other rolling stock.

Another object of the invention is to provide a construction including a sub-support beneath the ties and extending longitudinally of the rails and embedded in the foundation or road bed, and coupled to the rails through the ties.

20 The marked increase in the weight of the rolling stock of present day railway construction requires a corresponding increase in the strength and stability of the road bed, including the rails, ties and the supports therefor, and the improved structure herein disclosed is designed to effectually accomplish the above results and prevent any tendency of the rails and ties to settle or work loose under the severe strains to which they are subjected.

25 With the usual construction of trackage, the constant pounding or hammering of the rolling stock, especially of the very heavy locomotives now used, soon produces an uneven surface over which the vehicles move, and thereby caused to quickly destroy the road bed units and materially increase the cost of maintenance.

30 In the usually constructed road bed including the single wood tie at spaced intervals, the ties are liable to be embedded in the ballast, especially where soft spots occur, and cause the rails to settle and the trains thereby to run unevenly and materially increasing the severity of the pounding action. Because of the lightness of the usual size of tie, the heavy locomotive and the cars that follow, cause the unevenness of the track to be accentuated and the locomotive and cars to sway from side to side, thus materially increasing the tendency of the rails and ties to be misplaced both vertically and transversely. To prevent the swaying of the rolling stock due to the uneven track, the 35 method comprising this invention is to prac-

tically widen and increase the ground area included in the spread and extent of the ties. While this applicant has shown and described the ties in pairs, it is believed to be within the purview of this invention to group the ties in any desired number.

40 The improved tie and its supports herein disclosed will effectually overcome the objections above noted, and hold the rails in position and effectually resist any tendency to displacement either laterally or vertically.

45 The improved device is best illustrated in the accompanying drawings, in which:

Figure 1 is a plan view of a section of a railway track constructed in accordance with my invention.

50 Figure 2 is a side elevation of the same.

Figure 3 is a transverse section enlarged, on the line 3—3 of Figure 1.

55 Figures 4 and 5 are detached perspective views from above and from beneath, of one of the improved tie plates.

60 The main or upper rails are represented conventionally at 10 and the lower or supporting rails at 11, and the ties at 12, the latter being disposed between the upper and lower rails, as shown.

65 The upper rails are the ones on which the rolling stock moves, while the lower rails are embedded in a foundation or bedding, preferably of rock ballast, gravel, hard clay, or the like, but may be of the usual broken stone or gravel ballast, and indicated conventionally at 13.

70 The ties 12 are arranged in pairs, as shown in Figure 1, with each alternate pair extending at a greater distance from the rail at one end than the other, and the remaining alternate pairs likewise extending at a greater distance from the rail at one end than at the other, but reversely to the first mentioned series of double ties.

75 In other words, the series of double ties are arranged in staggered relation.

80 By this means the transverse area of the tie support is materially increased without increasing the length of the ties.

85 The wide spread secured by the staggered arrangement of the double series of ties materially increases the ground footing or spread, equal to nearly four times the ordinary arrangement with the single tie, and will carry a material increase of weight of the rolling stock without deflection.

90 The lower or under rail materially in-

creases the stiffness and stability of the structure and helps to carry the heavy load of the train without vibration and holds up the top rail and relieves the bearing down 5 load and strain on the upper rail at any one point, and in addition holds up and supports the joints and ties of the upper rail, besides distributing the weight along the track in a similar manner to a truss carrying a load.

10 The joints of the single track rail as ordinarily constructed are liable to deflection under heavy loads, and require constant adjustment.

The lower rail materially increases the 15 stiffness and maintains the track in alignment, and prevents it from lateral displacement or working out of line, as the lower rail being embedded in the foundation and firmly bolted to the ties and to the upper 20 rail, effectually prevents any lateral displacement or creeping of the rails.

The whole track is firmly tied together and its weight materially increased which is 25 essential, and the bearing surface of the ties also materially increased and maintains the 30 bearings for the ties uniform and carrying the load equally as the train passes over.

No single tie or pair of ties can become embedded in the ballast at a soft spot, nor to 35 give way under the load.

After the ties and rails are bolted together, the ballast will be tamped under the ties and between and under the rails and outside of the same, as illustrated in Figure 3, and the 40 track levelled up to line.

The lower supporting rails 11 may be old worn out rails, the two sets of rails being united by clamp bolts 14 and clamp plates 45, as shown.

40 The joints between the upper rails are reinforced by the usual fish or clamp plates represented at 16, while the joints of the lower or supporting rails are likewise supported by like fish or clamp plates indicated at 17.

45 The joints of the lower rails will be disposed intermediate the joints of the upper rails as illustrated in Figure 2.

The ballast 13 may be further supported, 50 if required, by a course of broken stone as indicated at 18.

What is claimed and desired to be secured by Letters Patent is:—

1. In railway construction the ties arranged in spaced pairs, the units of each pair disposed side by side, with each alternate pair of ties extended to a greater distance from one rail than from the other, and the remaining alternate pairs of ties extend-

ed to a greater distance from said other rail 60 than from the first mentioned rail.

2. In railway construction the ties arranged in spaced pairs, the units of each pair disposed side by side, with each alternate pair of ties extended to a greater distance 65 from one rail than from the other, the remaining alternate pairs of ties extended to a greater distance from said other rail than from the first mentioned rail, supports extending beneath the ties and in vertical alignment with the rails, and means for connecting the rails, ties and supports. 70

3. In railway construction the ties arranged in spaced pairs, the units of each pair disposed side by side with each alternate pair of ties extended to a greater distance 75 from one rail than from the other.

4. In railway construction, the ties arranged in spaced pairs, each pair forming a 80 separate unit, said units being arranged in staggered relation.

5. In railway tie construction, groups of ties, each group comprising a plurality of ties arranged lengthwise adjacent one to another, each group of ties being spaced from 85 a succeeding group, and each group having the ends of the ties arranged to extend to a greater distance beyond the track on one side and a lesser distance beyond the track on the other side, and one group of ties having its greatest extent on one side of the track and the succeeding group of ties having its greatest extent on the other side of the track. 90

6. In railway tie construction, groups of 95 ties, each group comprising a plurality of ties, and each group having the ends of the ties arranged to extend to a greater distance beyond the track on one side and a lesser distance beyond the track on the other side, and one group of ties having its greatest extent on one side of the track and the succeeding group of ties having its greatest extent on the other side of the track. 100

7. In railway tie construction, a plurality 105 of staggered groups of ties, rails supported thereby, and retaining means common to a plurality of ties of a group and to the adjacent rail.

8. In a railway tie construction, a plurality 110 of staggered groups of connected ties.

9. In a railway tie construction, a plurality 115 of staggered groups of connected ties, and rails supported thereby.

In testimony whereof I affix my signature.

GEORGE W. MULLER.
